UNITED STATES PATENT OFFICE.

CHARLES TELLIER, OF PARIS, FRANCE.

PRODUCTION OF MOTIVE POWER AND APPARATUS THEREFOR.

SPECIFICATION forming part of Letters Patent No. 439,258, dated October 28, 1890.

Application filed November 13, 1884. Serial No. 147,886. (No model.) Patented in France January 22, 1884, No. 159,851; in Belgium September 18, 1884, No. 66,340; in England September 20, 1884, No. 12,640; in Italy September 30, 1884, XXXIV, 303; in Portugal October 15, 1884, No. 957; in Austria-Hungary December 16, 1884, No. 35,516 and No. 52,873; in Spain April 23, 1885, No. 4,494; in Brazil June 6, 1885, No. 238; in Germany July 25, 1885, No. 36,133, and in India October 27, 1885, No. 126/1,016.

To all whom it may concern:

Be it known that I, CHARLES TELLIER, a citizen of the Republic of France, residing at Paris, France, have invented new and useful

5 Improvements in the Production of Motive Power and Apparatus Therefor, (patented in France by Letters Patent to the Société de Navigation Economique, No. 159,851, dated January 22, 1884; in Belgium by Letters 10 Patent No. 66,340, dated September 18, 1884; in Great Britain by Letters Patent No. 12,640, dated September 20, 1884; in Italy by Letters Patent, Vol. XXXIV, No. 303, dated September 30, 1884; in Austria-Hungary by Letters 15 Patent No. 35,516 and 52,873, dated December 16, 1884; in Portugal by Letters Patent No. 957, dated October 15, 1884; in Spain by Letters Patent No. 4,494, dated April 23, 1885; partly in Germany by Letters Patent No. 36,133, dated July 25, 1885; in Brazil by Letters Patent No. 238, dated June 6, 1885, and in India by Letters Patent No. R. 20 126/1,016, dated October 27, 1885,) of which the following is a specification.

25 My invention is represented in the accompanying drawings, in which—

Figure 1 is an elevation of my machine or apparatus for producing motive power. Fig. 2 is a vertical section, partly in elevation, of the motor-cylinder. Fig. 3 is a horizontal section of the motor on the line Z' Z' of Fig. 1. Fig. 4 is a plan of the motor. Fig. 5 is a vertical section of the motor-piston. Fig. 6 is a vertical section of one of the interchangers. Fig. 7 is a vertical section of one of the force-pumps on the line y' y' of Fig. 3, and Fig. 8 represents the igniting-plug and adjacent parts.

My invention consists of an improved machine for producing motive power by the direct employment of certain combustible gases—such as hydrogen, carbonic oxide, carbonated hydrogen, &c.—and by effecting the combustion of these gases in the motor-cylinder by the improved means hereinafter described.

The combustible gases produced by any suitable apparatus, but preferably by my apparatus for producing combustible gases patented April 10, 1883, No. 275,437, are drawn in

in a cold state by the pump J. The construction of these pumps is represented in vertical section at Fig. 7. They are provided with suction and delivery valves T T', which are shown clearly in the section of the chest at T. They are also provided with cooling-chains 55 similar to those described in my former Letters Patent No. 275,437, dated the 10th day of April, 1883. The said chains heated by the gases are cooled by a current of cold water entering through the tube Z Z, Fig. 1, and passing to the openings Y and Y', Fig. 7. These pumps serve to receive through the openings b' b'' the combustible gases coming from the gas-producer. These gases are compressed and cooled by the pumps and then sent through 60 delivery-valves d'' d''''. Thence by means of an arrangement of tubes they pass to the lower part K of the interchanger E'. (Shown at Figs. 1 and 4, and detached in section at Fig. 6.) The gases enter the interchanger E' 65 through the opening K, pass around the cluster of tubes B''', and thence out through the opening K'. The tube O O, Fig. 1, then conducts them to the distributing slide-valve M', Figs. 1 and 2. The pump H, Figs. 1, 3, and 4, on the other hand, takes in atmospheric air. This pump, constructed exactly on the same principle as the pump J, compresses the air thus drawn in, at the same time cooling it. It forces this compressed air into the interchanger F, 75 Figs. 1 and 4, which is constructed like the interchanger E'. (Shown in section at Fig. 6.) The air thus drawn into the interchanger leaves through the opening K' and the tube O' O' and passes to the distributing slide-valve 80 M'. When this valve M' is opened, the gaseous mixture coming from the tubes O O O' O' is admitted into the cylinder until the admission-valve is closed. The said gases, having a pressure due to the action of the pumps, 85 drive the piston before them until the admission is stopped. Any suitable slides or valves can be employed for opening and closing this admission.

Fig. 2 illustrates the mode of distribution 95 which I prefer to employ, and which is hereinafter described.

When the admission is stopped by the op-

eration of the machine in a similar manner to that of a steam-engine—that is to say, by means of eccentrics or cams—the gaseous mixture is ignited by means of an electric spark 5 through the igniting-plug represented in Fig. 8. This igniting device U consists of a plug of insulating material $l\ l$, through which pass two wires m' and n' in communication with any suitable generator of electricity. A knob 10 operated by the crank, the head of the piston, or any other suitable movable part of the machine ignites the gaseous mixture at the required moment. As shown at U U, Fig. 3, one or more of these igniting apparatuses is 15 placed either on the bottoms or on the sides of the cylinder. When the ignition is effected, a pressure is produced greater than that of the admission in the cylinder. This pressure would cause the admission-slides r' to be 20 blown away if the precaution were not taken to place them between double plates, as represented at $c\ n$ and at $c\ f^2$, Fig. 5.

A side pump h^* , Fig. 1, at each stroke of the piston forces the necessary quantity of 25 water or cooling liquid to form the bath for the chains and to carry away the heat of compression. The liquid can afterward, if there is a scarcity of water, be passed through a cooling apparatus, so that it may be used 30 afresh. If water under pressure be available, the pump h^* could be dispensed with and it would be supplied through the tube Z Z, Fig. 1, to feed the pumps. Fig. 7 shows this tube 35 conducting the water to the openings $y\ y'$ through tubes provided with retaining-valves for preventing the return of the water backward during the period of compression. When the piston has completed its stroke, the gases escape through the exhaust-valves 40 D D', Fig. 2. These gases could be allowed to escape directly into the atmosphere if they did not possess any sensible heat; but as they are hot and it is important to utilize the heat 45 the gases are conducted through the tubes $l'\ l'$ and $g'\ g'$, Fig. 2. These tubes extend into a casing surrounding the cylinder, as shown in Figs. 2 and 4. (This casing is not indispensable.) In all cases the exhaust-gases are afterward conducted to the interchangers E' F 50 by the tubes L L G G and pass through the exchange-tubes B''', Fig. 6, and finally leave through the opening L', Fig. 6. Now around the tubes B''' I have caused the gases to pass 55 which go to the motor-cylinder, and as these gases, which arrive in a cold state, circulate in an opposite direction to the heated gaseous current leaving the motor-cylinder, an ex-

change of calorific takes place between them, so that the used and escaping gases are deprived of as much heat as possible, while, on the other hand, the gases which are passing to the motor-cylinder have the said heat imparted to them. The above is a description of the operation of the interchanger.

By reference to Fig. 4 it will be seen that, if desired, the gases can be caused to escape through the tube M'', and thence might be conducted by a suitable pipe directly to the interchangers; or they could, if desired, be caused to pass through a jacket surrounding the cylinder, so as to prevent it from becoming cool, and then be caused to escape through the tubes $g'\ g'\ l'\ l'$.

The movement of the motor-piston B⁵ B⁵, Fig. 2, is transmitted by the rod V⁵ to a slide W, which carries a connecting-bar R R, which, as shown in Fig. 1, actuates the force-pumps I J H, and by means of connecting-rods S S and cranks p⁵ p⁵ p⁵ p⁵ rotates the motor-shaft P⁶ P⁶.

Fig. 5 shows a section of the piston. This piston is constructed with springs r'' r'', carrying a bronze or other anti-friction metal packing s''' s'''. In order to cause these springs to bear on the periphery of the cylinder, I provide sockets u u, in which are placed spiral springs bearing against small plugs v' v', which press against the springs r'' r'', and consequently assist their action.

To put the machine in motion, a few revolutions are given by hand to the fly-wheel. The pumps, being thus operated, will draw in the combustible gases coming from the gas-producer, and as soon as these gases enter the motor-cylinder electric communication is established and motion is produced.

Having now particularly described and ascertained the nature of the said invention and in what manner the same is to be performed, I declare that what I claim is—

In a motor in which the power developed by the combustion of a gaseous mixture is utilized, the combination, with the suction and force pumps having the calorific chains applied and performing the duty as set forth, of a motor-piston and the reheaters E' and F, these parts being arranged and operating substantially as and for the purposes described.

CHARLES TELLIER.
